(57) **CLAIM**

The ornamental design for a magnetic armband, as shown and described.

DESCRIPTION

FIG. 1 is a front perspective view of a magnetic armband, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof, the bottom plan view is a mirror image thereof; and,

FIG. 7 is a perspective view of the magnetic armband, shown in a used condition.

The broken lines illustrating a human arm and magnetizable objects in FIG. 7 depict environmental subject matter that forms no part of the claimed design, while the remaining broken lines shown in the drawings represent claimed subject matter (stitching).
